Corporation of America, a corporation of Dela-
ware

Application December 8, 1932, Serial No. 646,265
In Great Britain December 30, 1931

7 Claims. (Cl. 91—53)

This invention relates to the treatment of textile fabrics, and in particular to the coating or filling of such fabrics.

The object of the invention is to enable fabrics to be given an even coating or filling in a simple and expeditious manner.

According to the invention, the coating or filling is spread over the fabric while the fabric is passing over a resilient bed, the resilient bed enabling even spreading, notwithstanding any unevenness in the fabric being treated.

The resilient bed is conveniently formed by stretching a sheet of rubber or like resilient material over a gap arranged opposite to the spreading means, so that the sheet is free to yield under any unevenness, and especially local unevenness, of the fabric. The bed may also be arranged to yield as a whole; for example, the bed may be carried on a member mounted on springs or other resilient means. A doctor knife affords a convenient means for effecting even spreading, and the subsequent description is directed principally to the use of such knife as the spreading means.

The coating or filling may be applied to the fabric prior to its reaching the doctor knife in any convenient manner. For example, it may be poured on to the fabric so as to form a pool or roll along the doctor knife. The supply of the filling material is preferably controlled so as to maintain the pool or roll substantially uniform in size, thus keeping the spreading effort required fairly constant. The width of such pool or roll may be adjusted by means of boundary plates which confine the coating or filling material to the width of fabric to be treated.

The doctor knife is preferably adjustable in order to provide for different thicknesses of fabric and coating layers. Such adjustability may be provided both for the height of the knife and its angularity with respect to the fabric. Means may be provided for drying the treated fabric continuously with the coating and filling operation.

Though the invention is applicable to the coating or filling of all kinds of fabric with any desired material, it is of particular advantage in the filling of fabrics adapted to be used as linings. Such materials require to have a firm, full and springy yet smooth finish, and particularly in the case of lighter fabrics, a filling is required to impart such finish. This filling is usually effected by coating the fabric with gum which, in order to avoid any risk of spoiling the appearance of the fabric, is applied to the back

only. By the use of filling materials of sufficient viscosity, a coating can be applied according to the invention which does not penetrate to the face of the fabric, the evenness with which the coating can be imparted by the use of the resilient bed in conjunction with the doctor blade affording an adequate safeguard against such penetration.

The invention will now be described in greater detail with reference to the accompanying drawing, but it is to be understood that this description is given by way of example only and is in no respect limitative.

Fig. 1 is a cross-sectional elevation of a form of apparatus according to the invention;

Fig. 2 is a plan view of part of Fig. 1; and

Fig. 3 shows in cross-sectional elevation a detail of Fig. 1 to an enlarged scale.

As shown in Fig. 1, a batch roll of fabric 12 to be treated, on a core 13, is supported by a spindle 14 in open bearings 15 formed in brackets 16 carried on a pair of end-frames 17. Further brackets 18 on the end-frames 17 provide bearings for a series of tension rollers 19, 20, 21 which extend between the frame ends 17.

The fabric, denoted at 22, is led from the batch roll 12 and over and under the tension rollers 19, 20, 21 to a resilient bed comprising a reinforced rubber sheet 23 stretched over the upper face of a wooden beam 24 extending between the frame ends 17.

Along the length of the beam 24 is a recess 25, and, as shown clearly in Fig. 3, the reinforced rubber sheet extends over the recess 25 and is adjustable as to tension, one edge of the sheet 90 being fixed to the beam 24 at 26 while the other edge is secured in a clamp 27 having a threaded shank 28 which is drawn through a plate 29 attached to the underside of the beam 24 by a nut 30.

Two frames 31, 31 are mounted upon the end frame 17 and are slotted vertically (Fig. 1) at 32 to house blocks 50 carrying trunnions 33 of a bar 34 which extends between the frames 17 and carries a downwardly pointing doctor knife 35. Hand wheels 38, 38 mounted on vertical screwed shafts 39, 39 extending partly down the slots 32 are adapted to raise or lower the trunnions 33 and bar 34 so that the edge of the doctor knife can be raised or lowered relative to the resilient bed.

A further hand wheel 40 is attached to one extremity of a horizontal shaft 41 borne in a bracket 42 mounted on one of the trunnions 33 and on rotation of the hand wheel 40 the angularity of

the doctor knife can be adjusted through a worm gear 43 on the shaft 41 and bar 34.

The coating or filling is supplied from a tank 36, and is applied to the fabric at a point a little 5 in advance of the doctor knife 35 through a pipe 37 extending from the tank 36 to a position above the desired point of application. The rate of flow of filling material from the tank 36 to the fabric is controllable by a valve 371 in the pipe 37, and 10 may be such as to maintain a pool of filling material of substantially uniform size before the doctor knife 35 thus keeping the spreading effort required fairly constant. In order to retain the pool of filling material upon the fabric, the last 15 tension roller 21 is maintained at substantially the same level as the resilient bed, and the width of the pool is controlled by boundary plates 48 adjustably mounted on a bar 49 outstanding from the doctor knife 35, so as to be readily adapted to 20 any width of fabric being treated.

The fabric is led from the tension rollers over the rubber sheet 23 of the resilient bed and out of the machine. During its progress beneath the doctor blade it is supported in a resilient manner 25 by the rubber sheet 23 only and in operation the doctor knife 35 is maintained somewhat out of the vertical with its edge pointing towards the batch roll 12. The doctor knife can thus be adjusted to spread the coating evenly over the fabric in 30 any desired thickness, the rubber sheet 23 of the resilient bed enabling evenness to be maintained in the case of unevenness in the fabric, even where such unevenness is local and not across the full width of the fabric. To allow for unevenness 35 across the full width of the fabric, the resilient bed as a whole is free to give and for this purpose the beam 24 supporting the rubber sheet 23 is mounted on coil springs 46, 46 (see Fig. 3) surrounding pegs 47, 47 attached to a wooden block 40 45 secured to the end frames 17.

The fabric 22 is drawn through the apparatus by means of a rotatable drying cylinder or "can" 52 co-operating with a nip roll 53.

The back of the fabric rests on the drying cylinder 52, thus allowing heat from the cylinder to penetrate and dry the filling material upon the face of the fabric. The fabric may be passed around any number of such cylinders depending on the amount of heat which may safely be applied to the fabric during one drying period. It 50 is preferred, however, to avoid a multiplicity of drying operations thus avoiding danger of the partly dried fabric picking up scales of dried filling material from the parts of the drying apparatus which necessarily contact with the treated 55 surface of the fabric. Conveniently, therefore, one drying cylinder of large diameter is employed. The drying apparatus may be arranged to run in series with a stenter for finishing the fabric as 60 will be well understood.

What we claim and desire to secure by Letters Patent is:—

1. Apparatus for applying coating or filling material evenly to a fabric comprising spreading means, a support, a sheet of resilient material 65 stretched across said support in proximity to the spreading means, means to hold said support stationary but resiliently with respect to the spreading means, and means adapted to draw the 70 fabric over the sheet and between the sheet and the spreading means so that by the resiliency of the material of the sheet and the resilient mounting of the support for the sheet, the sheet is capable of yielding to local and general unevenness of the fabric so as to cause an even coat-

ing to be applied to the fabric by the spreading means.

2. Apparatus for applying coating or filling material evenly to a fabric comprising spreading means, a support, a sheet of rubber stretched across said support in proximity to the spreading means, means to hold said support stationary but resiliently with respect to the spreading means, and means adapted to draw the fabric over the rubber sheet and between the sheet and the spreading means so that by the resiliency of the rubber sheet and the resilient mounting of the support for the sheet, the sheet is capable of yielding to local and general unevenness of the fabric so as to cause an even coating to be applied to the fabric by the spreading means. 80

3. Apparatus for applying coating or filling material evenly to a fabric comprising a spreading doctor knife, a beam having a channel in its upper surface, a sheet of resilient material stretched across said beam in proximity to the doctor knife, means to hold said beam stationary but resiliently with respect to said doctor knife, and means adapted to draw the fabric over the sheet and between the sheet and the doctor knife so that by the resiliency of the material of the sheet and the resilient mounting of the beam, the sheet is capable of yielding to local and general unevenness of the fabric so as to cause an even coating to be applied to the fabric by the spreading means. 90

4. Apparatus for applying coating or filling material evenly to a fabric comprising a spreading doctor knife, a beam having a channel in its upper surface, a rubber sheet stretched across said beam in proximity to the doctor knife, means to hold the said beam stationary but resiliently with respect to said doctor knife, and means adapted to draw the fabric over the sheet and between the sheet and the doctor knife so that by the resiliency of the rubber sheet and the resilient mounting of the beam, the sheet is capable of yielding to local and general unevenness of the fabric so as to cause an even coating to be applied to the fabric by the spreading means. 100

5. Apparatus for applying coating or filling material evenly to a fabric comprising a spreading doctor knife, a beam having a channel in its upper surface, a rubber sheet stretched across said beam in proximity to the doctor knife, supporting springs to hold said beam stationary but resiliently with respect to said doctor knife, and means adapted to draw the fabric over the sheet and between the sheet and the doctor knife so that by the resiliency of the rubber sheet and the spring mounting of the beam the sheet is capable of yielding to local and general unevenness of the fabric so as to cause an even coating to be applied to the fabric by the spreading means. 110

6. Apparatus for applying coating or filling material evenly to a fabric comprising a spreading doctor knife, a beam having a channel in its upper surface, a rubber sheet stretched across said beam in proximity to the doctor knife, tensioning means on said beam for imparting tension to said rubber sheet, supporting springs to hold said beam stationary, but resiliently with respect to said doctor knife, and means adapted to draw the fabric over the sheet and between the sheet and the doctor knife so that by the resiliency of the rubber sheet and the spring mounting of the beam the sheet is capable of yielding to local and general unevenness of the fabric so 120

as to cause an even coating to be applied to the fabric by the spreading means.

7. Apparatus for applying coating or filling material evenly to a fabric comprising a spreading doctor knife, a beam having a channel in its upper surface, a rubber sheet stretched across said beam in proximity to the doctor knife, tensioning means on said beam for imparting tension to said rubber sheet, supporting springs to hold said beam stationary but resiliently with respect to said doctor knife, means adapted to

draw the fabric over the sheet and between the sheet and the doctor knife so that by the resiliency of the sheet and the spring mounting of the beam, the sheet is capable of yielding to local and general unevenness of the fabric so as to cause an even coating to be applied to the fabric by the spreading means, and a drying apparatus adapted to receive the treated fabric drawn past the spreading doctor knife.
